UNITED STATES PATENT OFFICE.

MILAN KNEZEVICH, OF AKRON, OHIO.

BATTERY.

Application filed November 26, 1924. Serial No. 752,426.

To all whom it may concern:

Be it known that I, MILAN KNEZEVICH, a citizen of Yugoslavia S. H. S., residing at Akron, in the county of Summit and State of Ohio, have invented certain new and useful Improvements in Batteries, of which the following is a specification.

This invention relates to new and useful improvements in batteries.

10 The primary object of the invention is to provide a novel form of electrodes for use in wet cell batteries.

15 Other objects and advantages of the invention will be apparent during the course of the following description.

In the accompanying drawings forming a part of this specification and in which like numerals are employed for designating like parts throughout the same,

20 Figure 1 is a top plan view of the apparatus embodying this invention,

Figure 2 is a vertical sectional view taken upon line II—II of Fig. 1,

25 Figure 3 is a perspective view of one form of electrode employed, and

Figure 4 is a perspective view of the other form of electrode employed.

30 In the drawings, wherein for the purpose of illustration is shown a preferred embodiment of this invention, the numerals 5 and 6 designate separate jars, preferably formed of porcelain, of about one gallon capacity each.

35 The jars 5 and 6 are to be filled to the level indicated in Fig. 2 with a solution consisting of two pounds of blue vitriol and distilled water.

40 In Fig. 3 there is shown a strand of copper wire, preferably of about three-eighths of an inch in diameter, which copper wire is bent to provide the straight conducting portion 8, the depending U-shaped bend 9 at one end thereof, the laterally projecting conducting portion 10 at the remaining end of the U-shaped bend 9, and the straight depending portion 11 at the remaining end of the conducting portion 10. This element is to be associated with the jars 5 and 6 by positioning the depending straight portion 11

45 in the jar 5 and the depending U-shaped bend 9 in the jar 6, the free end of the straight conducting portion 8 extending from

the jar 6 to act as a lead off or connection terminal.

In Fig. 4 there is shown two blocks 13 and 14 which are each formed by a suitable molding operation from four pounds of amalgamated zinc. Each of these blocks has projecting from the upper surface thereof of an apertured ear 15 which has extending thru the aperture a supporting rod 16. A strand of copper wire, preferably of three-eighths of an inch in diameter, is formed in the same manner as the copper wire shown in Fig. 3 and includes the straight conducting portion 8^a, the depending U-shaped bend 9^a, the straight conducting portion 10^a, and the depending straight portion 11^a. The depending U-shaped bend 9^a is to be molded in the block 14 while the depending straight portion 11^a is to be molded in the block 13, it being understood that the portions of the wire strand and the ears 15 are embedded in the blocks 13 and 14 when the latter are formed in the manner previously described. This structure is associated with the various jars by arranging the block 13 in the jar 6 with the supporting rod 16 traversing the top of the same and supported and insulated therefrom by the blocks 12^a, the block 14 arranged in the jar 5 with its supporting rod 16 traversing and resting upon the upper edge of this jar by means of the insulating blocks 12^a, and with the straight conducting portion 8^a extending across the top of the jar 7 and supported at its free end by the insulating block 12. It will be noticed, by inspecting Figs. 2 and 3, that the amalgamated zinc blocks 13 and 14 extend less than half of the length of the jars 5 and 6.

It is to be understood that the form of this invention herewith shown and described is to be taken as a preferred example of the same, and that various changes in the shape, size, and arrangement of parts may be resorted to without departing from the spirit of the invention or the scope of the subjoined claim.

Having thus described the invention, I claim:—

In a device of the type described, a pair of open top jars, an electrolytic solution in each jar, a pair of electrodes of block formation received in said jars, an apertured

ear projecting from the top of each electrode, a rod projecting through the aperture of each ear to act as a support for the electrode by engaging the top of a jar, a conductor for said electrodes to inseparably connect the same, said conductor including depending portions permanently embedded in said electrodes, a portion connecting the

embedded portions, and a lead-off part projecting laterally from one electrode, and a second pair of electrodes for said jars having formed integrally therewith a connecting conductor and a lead off conductor.

In testimony whereof I affix my signature.

MILAN KNEZEVICH.
